SPRINKLER HEAD

Charles M. Boroughs, Seattle, Wash.

Application February 12, 1947; Serial No. 728,101

3 Claims. (Cl. 299—145)

1

This invention relates to sprinkler heads, and has for its general object to provide an improved device of this nature which will deliver water in a circular pattern and in a manner to effectuate a more uniform wetting of the area under treatment than has been possible with prior designs of sprinkler heads. With presently available sprinkler heads, the ejected water usually takes the form of a fountain or umbrella spray, and there have been also devised several sprinkler heads which are designed with the express intention of projecting the delivered water along a substantially flat course. Both types of spray have their advantages. A fountain or umbrella delivery can be made to span a wide compass but leaves a comparatively dry inner ring immediately adjacent to the head and there is also a tendency for the delivered water to fall in rather large droplets which is quite objectionable when watering plant life having fragile foliage. Also, there are many instances where it is desirable to soak the ground about the base of a shrub or shrubs rather than to apply the water upon the leaves, and the flat spray becomes a specific for this purpose. In addition to permitting this under-foliage watering of shrubbery, the flat spray will better accomplish a wetting-down function where wind is present from the self-evident fact that the spray hugs the ground and is not unduly dispersed. The present invention has the further and particular object of providing a sprinkler head which is capable of delivering either the fountain or the flat type of spray, selectively, and which in addition may be employed, where desired, to deliver both a fountain and a flat spray simultaneously.

The invention has the still further object of providing a compact sprinkler head which may be inexpensively produced and which will give long and trouble-free service to the user.

The particular design and the arrangement of parts which operate to accomplish the ends in view will become apparent in the course of the following description taken in connection with the accompanying drawing illustrating the now-preferred embodiment of the improved sprinkler head, the invention consisting in the novel construction and in the adaptation and combination of parts hereinafter described and claimed.

In said drawing:

Figure 1 is a view taken partly in longitudinal vertical section and partly in side elevation, and portraying, fragmentarily, a water-supply hose attached to the head; and

Fig. 2 is a horizontal sectional view on line 2—2 of Fig. 1.

Having reference to the drawing, the head of the present invention comprises a body member denoted by the numeral 3 preferably cast from brass to present a comparatively heavy base 4

and formed above this base with a cylindrical open-top chamber 5, there being provided a side branch 6 leading to the chamber and which is provided with a suitable fitting 7 for coupling the branch to the mating fitting 8 of a water hose 9. Formed in the base and open to the chamber is a centrally placed threaded socket 10.

The open end of the chamber is ground to present a bevelled valve seat 11, and the valve therefor surmounts a stem 12 which threads into the socket 10, there being received about the stem a compression spring 13 bearing by one of its ends against the floor of the chamber and by its other end against the underside of the valve.

The bevelled face 14 of the valve is ground from the underside of an externally threaded boss 15, and there is provided to work on these threads a knurled collar or nut 16 having an O. D. dimension appreciably greater than the diameter of the valve seat and characterized in that its underside is faced flat. Above the threaded boss, the valve-forming body presents a knurled head 17. This head is recessed to produce a secondary water chamber 18, and giving access to this secondary chamber from the sub-adjacent main water chamber 5 are a severality of vertical ducts 20 having their admission ends circumferentially spaced in surrounding relation to the root end of the stem. Press-fitted into the open end of the chamber 18 is a disk 21, and presented thereby is a bevelled valve seat 22 arranged to complement a second valve 23, and this second valve which, like the first-named valve, is made adjustable through rotary movement, is formed with a knurled head 24 and has a threaded stem 25 working in a threaded socket 26 bored in the body of the first-named valve. The threads of the stem 25 are made comparatively fine to obviate the need for any spring in holding the same against movement.

In using the present sprinkler head, and assuming that it is desired to produce either a flat or a fountain spray, singly, it becomes necessary only that the secondary valve be closed upon its seat and the main valve opened in the degree desired, and the operator, to obtain a fountain-like delivery, need only back off the spray-governing collar and the issuing water will then follow the unobstructed path of a cone describing a prolongation of the taper of the valve seat. Turning the collar down will perform interrupt this delivery and flatten out the spray in accordance with the degree to which the nut is brought into proximity to the body member 3. A regulation of the ports such as to leave only a thin crack through which the water may issue will create a fine mist spray. If, now, it becomes desirable to augment the horizontally delivered spray with a fountain-type head spray and which is particularly desirable as a means of covering

a wide scope while at the same time thoroughly wetting the ground throughout the area contained within the circle of the head spray, the secondary valve is opened in such degree as may be desired.

The described sprinkler head and the manner of its employment will, it is believed, be clear from the foregoing. Various departures from the embodiment which I have here elected to illustrate may obviously be resorted to without departing from the spirit of the invention, and no limitations are to be implied by reason of having particularly described such illustrated embodiment. It is my intention that the hereto annexed claims be read with the broadest scope commensurate with the language used.

What I claim is:

1. In a sprinkler head, the combination of a hollow body providing a water chamber arranged to be pressure fed from a source of water supply and having a discharge opening at the top circumscribed by a bevelled valve seat, said body presenting a flat face surrounding the valve seat, a complementing valve having a bevelled valve face closely fitting the valve seat and threadably connected with the body for moving the valve axially to open and close the discharge opening, an externally threaded boss made integral with the valve and located in concentric surmounting relation to the valve face, and a collar working on the threads of the boss and formed upon its underside with a substantially flat face overlying the said flat face of the hollow body and serving as a baffle and arranged by adjustment of the collar downwardly upon the boss to bring said baffle into a position whereat the same acts to variably break up and deflect an issuing stream of water travelling the path of an inverted hollow cone prescribed by the bevel of the valve seat.

2. The structure of claim 1 in which the said valve provides a second water chamber having

a top opening circumscribed by a bevelled valve seat, and a second valve having a valve face closely fitting the last-named valve seat and providing a depending integral stem threaded into the body of the first-named valve for moving the second-named valve into and from closed position, the body of the first-named valve providing water-supply ducts giving access for pressure water from the first-named to the second-named water chamber.

3. The sprinkler head of claim 2 in which the first-named valve presents a head above the said externally threaded boss knurled upon its periphery to facilitate adjustment of the first-named valve, and in which the second-named valve is itself provided with a head likewise knurled upon its periphery to facilitate adjustment of the second-named valve.
